UNITED STATES PATENT OFFICE.

WILLIAM W. SAYERS, OF PHILADELPHIA, PENNSYLVANIA, ASSIGNOR TO LINK-BELT COMPANY, OF CHICAGO, ILLINOIS, A CORPORATION OF ILLINOIS.

SKIP HOIST.

Application filed December 20, 1924. Serial No. 757,091.

To all whom it may concern:

Be it known that I, WILLIAM W. SAYERS, a citizen of the United States, residing at Philadelphia, in the county of Philadelphia and State of Pennsylvania, have invented a certain new and useful Improvement in Skip Hoists, of which the following is a specification.

This invention relates to a skip hoist and particularly to that type of skip hoist which discharges from a bin through an undercut gate into a moving bucket or car, and in which the movement of the gate is controlled by the movement of the car. It has for one object to provide in connection with an undercut gate, a car or bucket, a guide or baffle part controlled by the movement of the car and adapted to prevent spilling of material or excessive discharge. Another object is to provide such a baffle arrangement with an undercut gate and adapted to move with it. Other objects will appear from time to time throughout the specification and claims.

My invention is illustrated more or less diagrammatically in the accompanying drawings, wherein:

Figure 1 is a vertical cross section with parts in elevation showing the gate open and material being discharged into the bucket;

Figure 2 is a side elevation showing the same parts with the gate closed and the bucket raised from the filling position;

Figure 3 is an end elevation of the gate in the position shown in Figure 1.

Like parts are designated by like characters throughout.

A is a truck upon which the bucket moves. Although it is shown as being inclined here it might be vertical. The bucket moves along the track to any suitable filling point, being lowered beneath the gate and bin to be loaded and then raised to the dumping point. The details of this construction are not illustrated as they form no particular part of the present invention. A¹ is a bucket or skip adapted to travel along the track. It is provided with wheels A² A². A³ is a bale pivoted to the bucket preferably at A⁴. A⁵ is a cable attached to the bale and by means

of which the skip or bucket is raised and lowered.

B is a hopper or bin provided with a discharging bottom B¹ which is adapted to discharge into a chute B².

An undercut gate is provided to close the chute. It is formed of a cylindrical portion C¹ and end webs C. These webs extend rearwardly and carry counterweights C². The gate is pivoted on a shaft C³ which is carried on the chute B². C⁴ is an outwardly extending lip formed on the cylindrical portion C¹ of the undercut gate.

Pivoted on the shaft C³ is an open U-shaped guide D. It is provided with one or more guide and baffle plates D¹ D¹ which extend laterally across it. These plates may have stiffeners D². Where comparatively light material is carried these stiffeners are unnecessary, but where heavy material is carried and where the shock and wear on the plates D¹ is heavy and violent the stiffeners will be necessary, and some outside stiffener D³ may be used on the end of the member D.

The guide member D has a lip or flaring portion D⁴ which, when the parts are in the position shown in Figure 1, forms generally a continuation of the floor of the hopper B² and is engaged by and in contact with the lip C⁴ of the cylindrical portion C¹ of the gate. The guide D in the form of the invention illustrated herewith is fastened to and moves with the gate C.

Although I have shown an operative device, still it will be obvious that many changes might be made in size, shape and arrangement of parts without departing materially from the spirit of my invention; and I wish, therefore that my showing be taken as in a sense diagrammatic.

E E are pull down angles located on the outside of the guide D. They are adapted to be engaged by rollers F F carried on arms F¹ F¹ on the skip or bucket A.

The use and operation of my invention are as follows:

When the parts are in operation the counterweight swings down and raises the undercut gate, closing it and preventing the discharge of material from the hopper. The

open U-shaped guide, of course, moves with the gate to which it is attached.

When the device is used the bucket or skip is lowered and the engaging rollers on it come in contact with the pull down angles in the outside of the U-shaped guide, and as the downward excursion continues, the guide is swung downward and with it the gate. When the gate is sufficiently open to permit discharge, material flows through it and into the bucket. The material as it flows strikes one or the other of the guide or baffle plates and is deflected downward into the bucket.

The top of the guide is open and the position of the baffle plates within the guide is such that when the bucket is full the material in the guide member flows out of the open top. The baffle plates extend downward into the guide a sufficient distance so that material will take its angle of repose, and when in this position cannot flow out from the open top of the guide. Thus the guide and baffle plates prevent discharge of material from the top of the U-shaped guide member either when the material is rushing rapidly down with great violence or when it has come to rest or after it has come to rest.

When the skip starts on its upward movement the gate is permitted to close and it rotates in the closing direction, closing the avenue of discharge and raising the guide member. Finally the avenue of discharge is completely closed and the skip is raised along the track to the point where it is discharged. When its discharge is complete it starts down and the cycle of movement is repeated.

I claim:

1. In combination with a chute, a chute closing member, adapted to be moved to prevent discharge therethrough, in combination with an open guide member adapted to move with said closing member and to guide the discharge of material from the chute.

2. In combination with a chute, a chute closing member, adapted to be moved to prevent discharge therethrough, in combination with an open guide member adapted to move with said closing member and to guide the discharge of material from the chute and to prevent excess discharge of material.

3. In combination with a chute, an undercut gate adapted to be moved to prevent discharge through said chute, an open guide member mounted to move with said gate and adapted to guide the discharge of material from the chute.

4. In combination with a chute, a chute closing member, adapted to be moved to prevent discharge therethrough, in combination with an open guide member adapted to move with said closing member and to guide the discharge of material from the chute, and a baffle within and extending across said guide member.

5. In combination with a chute, an undercut gate adapted to be moved to prevent discharge through said chute, an open guide member mounted to move with said gate and adapted to guide the discharge of material from the chute, and a baffle within and extending across said guide member. 70

6. In a skip hoist, a chute, and a skip adapted to be filled therefrom, a chute closing member adapted to be moved to prevent discharge through said chute, in combination with an open guide member mounted to move with said closing member, and adapted to guide the discharge of material from the chute. 75

7. In a skip hoist, a chute, and a skip adapted to be filled therefrom, a chute closing member adapted to be moved to prevent discharge through said chute, in combination with an open guide member mounted to move with said closing member, and adapted to guide the discharge of material from the chute, and to bridge the gap between the end of said chute and said skip. 80

8. In a skip hoist, a chute, and a skip adapted to be filled therefrom, a chute closing member adapted to be moved to prevent discharge through said chute, in combination with an open guide member mounted to move with said closing member, and adapted to guide the discharge of material from the chute, said guide member being provided with a lip portion extending from the discharge end of said chute to said skip. 90

9. In a skip hoist, a chute, and a skip adapted to be filled therefrom, a chute closing member adapted to be moved to prevent discharge through said chute, in combination with an open guide member mounted to move with said closing member, and adapted to guide the discharge of material from the chute, said chute closing member adapted to be opened by the downward movement of said skip and provided with a counterweight whereby it is closed automatically as the skip moves upward. 100

10. In a skip hoist, a chute and a skip adapted to be filled therefrom, a chute closing member adapted to be moved to prevent discharge through said chute, in combination with an open guide member mounted to move with said closing member, and adapted to guide the discharge of material from the chute, said guide member being provided with a lip portion extending from the discharge end of said chute to said skip, said chute closing member adapted to be opened by the downward movement of said skip and provided with a counterweight whereby it is closed automatically as the skip moves upward. 115

11. In a skip hoist, in combination a chute and a skip adapted to be filled therefrom, an undercut gate adapted to be moved to prevent discharge through said chute, an open 120

- guide member mounted to move with said gate and adapted to guide the discharge of material from the chute.
12. In a skip hoist, a chute, and a skip adapted to be filled therefrom, a chute closing member adapted to be moved to prevent discharge through said chute, in combination with an open guide member mounted to move with said closing member, and adapted to guide the discharge of material from the chute, said guide member having a baffle within and extending across it.
13. In a skip hoist, a chute, and a skip adapted to be filled therefrom, a chute closing member adapted to be moved to prevent discharge through said chute, in combination with an open guide member mounted to move with said closing member, and adapted to guide the discharge of material from the chute, said guide member being provided with a lip portion extending from the discharge end of said chute to said skip, said guide member having a baffle within and extending across it.
14. In a skip hoist, in combination a chute and a skip adapted to be filled therefrom, an undercut gate adapted to be moved to prevent discharge through said chute, an open guide member mounted to move with said gate and adapted to guide the discharge of material from the chute, and to bridge the gap between the discharge end of said chute

and said skip, said guide member having within and extending across it a plurality of baffles.

15. In combination with a chute, a chute closing member adapted to move to prevent discharge therethrough, said member formed with a pair of side members and provided with a generally arcuate chute closing gate portion, and an open guide member adapted to move with said gate.

16. In combination with a chute, a chute closing member adapted to move to prevent discharge therethrough, said member formed with a pair of side members and provided with a generally arcuate chute closing gate portion, and an open guide member adapted to move with said gate, said guide member provided with a plurality of baffle plates.

17. In combination with a chute, a chute closing member, adapted to be moved to prevent discharge therethrough, in combination with an open guide member adapted to move with said closing member and to guide the discharge of material from the chute, said open guide member being provided with a plurality of baffle plates generally adjacent its open upper side.

Signed at Philadelphia, county of Philadelphia and State of Pennsylvania, this 12th day of December, 1924.

WILLIAM W. SAYERS.
